CHARLES ZEUNER, OF CINCINNATI, OHIO, ASSIGNOR TO M. GREENWOOD & CO., OF SAME PLACE.

Design No. 3,226, dated November 3, 1868.

DESIGN FOR A SHOVEL-AND-TONGS STAND.

The Schedule referred to in these Letters Patent and making part of the same.

To all whom it may concern:

Be it known that I, CHARLES ZEUNER, of the city of Cincinnati, in the county of Hamilton, and State of Ohio, have originated and designed a new Pattern for a Shovel-and-Tongs Stand, of which the following is a full and clear description, reference being had to the accompanying drawing, making a part of this specification.

The parts comprising the shovel-and-tongs stand, the "dish," "upright," "arms," and "handle," have the following configuration:

The "dish" A is of the form of a corrugated shell. Each corrugation has in relief an oak-leaf, a, the stem of which terminates near the foot of the "upright." Between the stems of the leaves a are acorns, a', pendent from the ring-course b. In the re-entering angles of the edge of the "dish" A is an ornamental triangular scroll, c. A large oval scroll, B, having the open-work

d within it, is the lower section of the upright C, above which are the reversed scrolls e, then a bead, f. The next section of the upright is made of leaf-shaped ornaments, g, which is surmounted by two circular columns alternating with beads, f. The capital consists of drooping leaves, h. The curved "arms" D surmount the capital, and are ornamented with leaves on the sides; their ends are rosettes, k. The handle E is of circular form, ornamented with leaves.

What I claim as new, of my invention, and desire to secure by Letters Patent, is—

The design for shovel-and-tongs stand, herein shown and described.

CHARLES ZEUNER.
